(57) **CLAIM**

The ornamental design for an installation panel for mats, as shown and described.

DESCRIPTION

FIG. 1 is a top perspective view of an installation panel for mats showing my new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof; and,

FIG. 8 is a right side view thereof.

The broken lines depict portions of the installation panel for mats in which the design is embodied and form no part of the claimed design.
